UNITED STATES PATENT OFFICE.

GEORGE S. RANDALL, OF MARSHFIELD, ASSIGNOR TO HOWARD C. BARNES,
OF BOSTON, MASSACHUSETTS.

BOX-FASTENER.

SPECIFICATION forming part of Letters Patent No. 316,823, dated April 28, 1885.

Application filed February 18, 1885. (No model.)

To all whom it may concern:

Be it known that I, GEORGE S. RANDALL, of Marshfield, in the county of Plymouth and State of Massachusetts, have invented a new and useful Improvement in Box-Fasteners, of which the following, taken in connection with the accompanying drawings, is a specification.

My invention relates to that class of box-
10 fasteners that are usually termed "self-latching clasps," and is made of a single piece of
spring metal, which is so cut and bent that
no joints are required for it, and it protrudes
but slightly from the face of the box to which
15 it is applied, the object being to construct from
a single piece of metal a spring-clasp. A sheet
of metal is cut in the form of a letter T. Then
the long part is bent so as to form a curve un-
der the upper part, and to terminate in the
20 vertical piece which serves to engage with
the pin on the lower part of the box. I attain
this object by the mechanism shown in the ac-
companying drawings, in which—

Figure 1 is an elevation of a violin-box with
25 my invention applied. Fig. 2 is a vertical
section through a part of the box to which the
clasp is applied, also showing the clasp in sec-
tion. Fig. 3 is a plan showing the shape of
the sheet metal before it is bent up. Fig. 4
30 shows in perspective, looking from the ante-
rior, the completed clasp.

In the drawings, A represents the upper part
of the box, and A' the lower part.

D is the clasp. This clasp is made of a piece
35 of sheet spring metal cut into the form shown
in Fig. 3. It is then bent into form shown

in Fig. 4, in which D' forms a cross-piece for
attaching the clasp to the box, the other part
being bent as indicated at d d' and D, Fig. 4
being, as already stated, a rear view of the 40
clasp. The clasp is fastened to the box by
pins or screws inserted in the openings e e.
The upper part of the box is recessed, as
shown at K, so as to receive the bent part d d'.
H, Figs. 2, 3, and 4, is a small opening, which 45
engages with the pin H', Fig. 2, and thus
holds the two parts of the box together. The
cross-piece D' also serves as a check to prevent
the flexible part D from being bent beyond its
limit of flexibility, thus preventing it from be- 50
coming set. By this form and arrangement I
make a very strong, simple, durable, and ex-
tremely cheap article.

What I claim as my invention is—

In a box - fastener, the combination of the 55
cross-piece D', having the flexible clasping-
piece D d d', the said flexible clasping-piece
passing slightly above, then back of the cross-
piece D', with the pin H', the cross-piece D'
serving to hold the flexible clasping-piece, and 60
also to check its outward motion, so that it
cannot be bent beyond its limit of flexibility,
substantially as described, and for the pur-
pose set forth.

In testimony whereof I have signed my 65
name to this specification, in the presence of
two subscribing witnesses, on this 14th day of
February, A. D. 1885.

GEORGE S. RANDALL.
